UNITED STATES PATENT OFFICE

2,542,325

GLASS TUBE BENDING APPARATUS

Alfred Greiner, Cleveland Heights, and August W. Seitz, Euclid, Ohio, assignors to General Electric Company, a corporation of New York

Application February 24, 1947, Serial No. 730,222

7 Claims. (Cl. 49—7)

1

Our invention relates to apparatus for bending tube or rod and more particularly relates to apparatus for automatically bending vitreous tube in a manner producing adjacent alternate bends therein.

One object of our invention is to provide apparatus for producing adjacent forward and reverse bends in a length of vitreous tube or rod in a single operation. According to our invention means are provided for heating a selected portion of the vitreous tube or rod and for displacing the opposite ends thereof both laterally and toward each other to bend the heated portion thereof to the particular form required.

Another object of our invention is to provide apparatus for offsetting the end of a vitreous exhaust tube extending from one end of a lamp in a ready and satisfactory manner whereby said apparatus can be used with semi-skilled labor in commercial manufacturing procedures. Our apparatus provides means for holding the vitreous exhaust tube and lamp during the heating step in the operation and means for moving said exhaust tube and said lamp with proper relation to each other to effect the desired bend and offset in said tube.

Another object of our invention is to provide vitreous tube bending apparatus of a construction suitable for use in combination with the tubular lamp bending apparatus disclosed in our copending application Serial No. 574,724, filed January 26, 1945, now Patent No. 2,494,872, and assigned to the assignee of the present invention. Our present invention provides a means for bending the vitreous exhaust tube of the lamp out of alignment with the end of said lamp so that the opposite end of said lamp can then be bent into close relation thereto. Combining both bending apparatuses eliminates a duplication of holding means and certain manual operations, thereby reducing the time taken for said operations and the cost and energy required therefore.

Still further objects and advantages of our invention will appear from the following detailed description of species thereof and from the accompanying drawing.

In the drawing, Fig. 1 is a front elevation of tube bending apparatus of our invention; Figs. 2 and 3 are side elevations of said apparatus taken from the sections therethrough along lines 2—2 and 3—3 respectively with alternate positions of the holders and associated means in dot-dot-dash lines; Fig. 4 is a perspective view of the lamp holder of said apparatus; Fig. 5 is a perspective view of the means of raising and lowering the

2

lamp holder; Fig. 6 is a side elevation corresponding to Fig. 2 of modified tube bending apparatus; Fig. 7 is a perspective view of the means for supporting and actuating the tube holder of the modified apparatus; and Fig. 8 is a perspective view of the lamp holder of the modified apparatus and the means of opening and closing said lamp holder.

The first steps in the cycle of operation associated with the apparatus disclosed in Figs. 1 to 5 inclusive, consists in the manual insertion of the tubular lamp 1 into said apparatus by inserting the metal cap 2 at one end of said lamp 1 into the holder 3 and thereafter moving the lamp 1 and holder 3 upward to insert the exhaust tube 4 extending from said end into the movable holder 5 to the position shown. At the time of insertion, the holder 3 is located in the lowered position shown in dot-dot-dash lines in Fig. 3, and the bar 6 closing off the open mouth of the opening therein is swung to one side as shown in Fig. 4 so that the exhaust tube 4 is given clearance under the movable holder 5 and access is given to the open mouth of the holder 3. The lamp 1 is manipulated so that the annular groove 7 in the metal cap 2, which is permanently sealed to the end thereof, is aligned with the beveled inner edge 3' of the U-shaped opening 4' in the holder 3 and so that said metal cap 2 finally engages the beveled edge of the curved end of said opening. The bar 6 which is swung back across the opening and which is fixed in place by bringing the leg 8 thereof over and inserting it in the hole 9 in the holder 3 prevents movement of the metal disc 2 in the holder 3. When completely inserted, the lamp 1 which has considerable length hangs from the holder 3 and is kept from lateral and vertical movement through its engagement therewith.

The holder 3 is mounted on the lower end of a rod 10 extending from the slide 11 which slide 11 is located within ways in the bracket 12 extending from the frame 13 of the apparatus and which is confined in said ways by the plates 14 and 15. The lower position of the holder 3 is determined by the presence of a sleeve 16 (Figs. 2, 3 and 5) on the stud 17 extending from the slide 11, within the enlarged lower end of a double keyhole slot 18 in the bracket 12.

The lamp 1 and holder 3 are moved upward to carry the end of the exhaust tube 4 into the movable holder 5 by manual manipulation of the hand lever 19, which lever 19 is connected by a slot 19' therein to the sleeve 16 and is pivotally mounted on a horizontal arm 20 which is pivotally mounted

on a vertical pin 21 in yoke 22 extending from bracket 12. To move the holder 3 and slide 11 upward, the hand lever 19 is first pushed back against the resistance of the spring 23, which is located on the stud 17 between the flanged sleeve 16 and the washer 24, until said sleeve 16 is unlocked and withdrawn from the enlarged lower end 18' of slot 18 and then is raised to lift the sleeve 16, stud 17 and the slide 11, the stud 17 being carried through the narrow intermediate portion of slot 18. At the upper limit of the movement, the sleeve 16 is again forced by the expansion force of the spring 23 into the enlarged upper end 25 of slot 18 which locks the slide 11 in place.

The above described mechanism provides a positive means of aligning and directing the exhaust tube 4 of the lamp 1 into the movable holder 5 thereby avoiding possible breakage of said exhaust tube 4, and reduces the difficulty in handling the lamp 1 which in most instances is relatively long.

The end of the exhaust tube 4 extends up through the openings in the cap 26 (Fig. 3), the washer 27 and into the passage in the rubber gland 28 of the movable holder 5 which has the dual functions of gripping said exhaust tube 4 and of making a gas tight connection thereto. Only the first-mentioned function has a direct bearing on the exhaust tube bending operations of our apparatus although both functions are brought about by the next operation step of clamping of the rubber gland 28 about the exhaust tube 4 through manual upward movement of the hand lever 29 to the position shown. The rubber gland 28 is located in an opening in the body portion 30 of the holder 5 which, in turn, is mounted on the end of the hollow spindle 31 and has a passage therein normally allowing free movement of the exhaust tube 4 therein. The upward movement of the hand lever 29 which is pivoted on pins 32 (only one of which appears in Fig. 2) and which in combination with links 33 form a toggle joint connected to cap 26 produces a corresponding movement in the cap 26 which compresses the rubber gland 28 causing it to grip the exhaust tube 4 and seal said tube 4 to the body portion 30 of the holder 5. The pivot pins 32 and adjacent portion of the hand lever 29 lie in an opening 33' within the fixed collar 34 on the body portion 30 which opening restricts the movement of said hand lever 29 and allows only sufficient upward movement of said hand lever 29 to permit the pins 35 joining said lever 29 and the links 33 to pass center so that the rubber gland 28 is kept under compression. The remainder of the mounting means for the holder 5 comprises the slide 36 which engages the spindle 31, the slide carriage 37 which provides, in combination with plates 38 and 39, ways and means for holding the slide 36, and the bracket 49 which rests on a portion of the frame 13 and which provides, in combination with plates 41 and 42, ways and means for holding slide carriage 37.

The course of operation of the apparatus next provides for the heating of an intermediate portion of the exhaust tube 4 by the burners 43 and 44 which are moved down into operative relation thereto, as shown, by the manual rotation of the crank 45 (Fig. 1). The burners 43 and 44 are mounted on a circuitous manifold 46 attached to the arms 47-47 and are brought from a position at which the arms 47-47 rest on the stop screws 48 (as shown in dot-dot-dash lines in Fig. 3) to a position where said arms 47 rest on the stop

screws 49. Each arm 47 is fastened to the shaft 50 adjacent one of the bearing blocks 51-51 carried by the frame member 52 and is swung between positions through rotation of said shaft 50 by manual manipulation of the crank 45 which is attached to one end thereof.

The period of treatment of the exhaust tube 4 by the burners 43 and 44 is dependent on the visual observations of the operator of the apparatus and is terminated when the color of the heated portion of the exhaust tube 4 indicates it is in proper plastic condition to be bent. At such times, the operator again swings the crank 45 back to its former position thereby removing the burners 43 and 44 from operative relation from the exhaust tube 4 and immediately turns the knob 53 so as to displace the movable holder 5 in a lowering and lateral movement whereby said exhaust tube 4 is bent to the position shown in dot-dot-dash lines in Fig. 2.

The translational displacement of the movable holder 5 is such that adjacent alternate bends are made in the exhaust tube 4 and such that the opposite ends thereof retain their given relation although they are displaced toward and laterally of each other. In the present instance, the end portions of the exhaust tube 4 are aligned and at a given parallel relation at the start of the bending and are offset and still at their given parallel relation after the bending operation is completed. The bending movement of the movable holder 5 is produced by motion of the slide means comprised of both slide 36 and slide carriage 37 in their respective ways and is brought about by the rotation of the cam 54 which is connected to the knob 53 through shaft 53 universal joint 56 and shaft 57. Shafts 55 and 57 are supported by the bearing blocks 58 and 59 respectively which are mounted on the bracket 40 and frame 13 respectively. Rotation of cam 54 turns it from a position where the extreme thickness or high point thereof is below and supporting the slide carriage 37 to a point where a minimum thickness or low point of said cam 54 is below the slide carriage 37 thereby allowing the entire weight of the holder 5 and other parts of the apparatus mounted on said slide carriage 37 to effect the bending. The lateral motion of the holder 5 occurs at the same time as the downward motion since the link 60 which is connected to bracket 49 by pin 61 and the slide 36 by pin 62 draws said slide 36 nearer the bracket 49 as said slide 36 is lowered. The limits of rotation of the cam 54 and, accordingly, the extent of the movement of the holder 5 is determined by the engagement of the stud 63 with portions of the plate 41 at the positions of the cam 54 shown in full and dot-dot-dash lines in Fig. 2.

Following the bending of the exhaust tube 4 a short interval is allowed to lapse to permit said exhaust tube 4 to cool sufficiently to regain its rigidity whereupon the manual operations necessary to separate the lamp 1 from the apparatus are performed or such other operations necessary to the manufacture of the lamp 1 are carried out. The present apparatus is well adapted to be combined with other apparatus for bending the lamp 1 to some configuration and in particular to be combined with the bending apparatus in our copending application Serial No. 574,724, filed January 26, 1945, now Patent No. 2,494,872, and assigned to the assignee of the present invention which apparatus bends said lamp 1 to almost a complete circle. The bend

in the exhaust tube 4 offsets said tube 4 so that it does not interfere with the bending of the opposite end (not shown) of the lamp to a close relation to the end thereof held by holder 3. Further, the holder 3 provides the means of gripping and supporting one end of the lamp 1, and the movable holder 5 provides the means of introducing a pressure of gas into said lamp 1 during the lamp bending operation. The gas is introduced into the open end of the exhaust tube 4 through the connection made to a source thereof (not shown) by the passages in the body 30 of the holder 5, spindle 31 and flexible hose 64.

The completed lamp 1 is removed from our apparatus in the same manner in every instance, the first step being the lowering of the hand lever 29 to unclamp the exhaust tube 4 from the movable holder 5; the second, being the lowering of the hand lever 19 to separate said exhaust tube 4 from said movable holder 5; and the third, being the lifting and swinging of the bar 6 to one side to allow removal of the metal cap 2 and lamp 1 from holder 3. Finally, a rotative adjustment is given knob 53 to raise and align the movable holder 5 with the holder 3 to place all parts of the apparatus in position for a succeeding cycle of operation.

The modification of our apparatus appearing in Figs. 6, 7 and 8 differs from the above-described apparatus in that the lamp 1 is gripped and supported by a holder 65 having similarly shaped halves 66 and 67, the former fastened to the post 68 extending from the slide 11 and the latter fastened to a rod 69 extending through said post 68 to the hand lever 70. The lamp 1 is inserted in the holder 65 by first moving the hand lever 70 so that movable half 67 of the holder 65 is swung outward giving access to the center thereof and then placing the cap 2 in proper engagement with the stationary half 66. The subsequent release of the hand lever 70 allows the contraction force of the spring 71 which extends between said hand lever 70 and a post 72 extending from the bottom of the slide 11 to close the movable half 67 of the holder 65 on the cap 2 of the lamp 1 causing it to be held securely in place. A guide pin 73 extending from the end of the half 67 of the holder 65 and entering into a hole in the half 66 of said holder 65 aligns said halves 66 and 67.

Succeeding operations in the use of the modification of our apparatus include the raising of the hand lever 19 to effect a corresponding movement of the slide 11 and holder 65 and cause the insertion of the end of the exhaust tube 4 into the movable holder 5. The hand lever 29 is then raised to the position shown in Fig. 6 to cause the holder 5 to grip and make a gas tight connection to the exhaust tube 4 in the same manner as previously described. In the present instance the support for the holder 5 is differently constructed and comprises a somewhat shorter hollow spindle 74 in engagement with the body 30 of the holder 5 and a slide block 75 for supporting the hollow spindle 74 and, through a passage (not shown) therein, making a suitable connection between said hollow spindle 74 and the pipe nipple 76 and flexible hose 64. Corresponding plates 77 and 78 (Fig. 7) extending from the bracket 79 on the frame 13 at opposite sides of the slide block 75 confine said slide block 75 to slide ways in a plane through the holders 5 and 65 whereas corresponding keys 80-80 attached to said slide block 75 and entering into diagonal slots 81 in the plates 77 and 78 further restrict

said slide block 75 to a definite path of movement both toward and laterally of the holder 65 in said plane. A separator plate 82 attached to the free ends of the plates 77 and 78 completes and strengthens the assembly.

As in the previous instance, that portion of the exhaust tube 4 which is to be bent is heated to a plastic condition by the fires from opposed burners (only burner 44 being shown in the present instance) which are movably mounted through the manifold 46, arm 47 and shaft 50. When the heating operation is complete the burners are swung up out of the way, as before, and an adjustment to the hand lever 83 is made which causes the movable holder 5 to travel toward and laterally of the holder 65 along a path determined by the cam slots 81 and making an acute angle with the line of alignment between the holders 5 and 65 thereby bending the exhaust tube 4 as desired. The hand lever 83 is mounted on one end of a shaft 84 carried by the plates 77 and 78 and, when adjusted, swings the arm 85 which is attached to said shaft 84 and which engages a pin 86 joining the keys 80 so that said keys 80 and the slide block 75 are moved in the direction of the slots 81 thereby effecting the desired translational motion in the movable holder 5. The movement is complete when the end of arm 85 engages the end of the stop pin 87 at which time the exhaust tube 4 has the shape shown in the dot-dot-dash lines of Fig. 2.

An interval of time is allowed to lapse to permit the exhaust tube 4 to cool and become hard whereupon the succeeding step in the manufacturing cycle takes place. This may consist either of the removal of the lamp 1 from the apparatus or the operations of bending the lamp 1 to some other form and then removing it. The lamp bending operation can be performed without removal of the lamp 1 from the modification of our apparatus shown in Figs. 6, 7 and 8 since said apparatus can function in combination with our lamp bending apparatus disclosed in patent application Serial No. 574,724, now Patent No. 2,494,872, hereinbefore referred to in the same manner as our previously described apparatus. The lamp 1 is removed from the modified apparatus by releasing the exhaust tube 4 from the movable holder 5 by manually lowering hand lever 29 and then by releasing the metal cap 2 from holder 65 by manually adjusting hand lever 70. The holders 5 and 65 must be moved to higher and lower positions respectively by manual adjustment of hand levers 83 and 19 respectively before the succeeding cycle of operations of the apparatus can be started.

Other more limited modifications of the apparatus still within the scope of our invention will be readily apparent to those skilled in the art.

What we claim as new and desire to secure by Letters Patent of the United States is:

1. Apparatus for bending a vitreous tube comprising means for heating an intermediate portion of the tube to a plastic condition, support means adjacent the heating means for causing one end of the tube to be retained at a fixed position, a holder similarly located adjacent the heating means engaging the opposite end of the tube for retaining and holding said end of the tube in a given relation to the support means, a slide for supporting the holder, ways defining a path of movement for the slide laterally of the support means, means engaging the slide and

the ways for moving said slide in said ways and the said ways toward the support means to produce adjacent alternate bends in the plastic portion of the vitreous tube.

2. Apparatus for bending a vitreous tube comprising means for heating an intermediate portion of the tube to a plastic condition, support means adjacent the heating means for causing one end of the tube to be retained at a fixed position, a holder similarly located adjacent the heating means engaging the opposite end of the tube for retaining and holding said end of the tube in a given relation to the support means, a slide for supporting the holder, ways defining a path of movement for the slide laterally of the support means, a link located within the plane of the path defined by the ways and joining a pivot on the slide and a stationary pivot offset laterally therefrom, and means for moving the ways toward the support means both to displace the slide and holder correspondingly and through the consequent sideward pull of the link to displace said slide and said holder laterally to produce adjacent alternate bends in the plastic portion of the vitreous tube.

3. Apparatus for bending a vitreous tube comprising means for heating an intermediate portion of the tube to a plastic condition, support means adjacent the heating means for causing one end of the tube to be retained at a fixed position, a holder similarly located adjacent the heating means engaging the opposite end of the tube for retaining and holding said end of the tube in a given relation to the support means, a slide for supporting the holder, a second slide having ways defining a path of movement of the first-mentioned slide laterally of the said support means, ways for the second slide defining a single path of movement in the plane of the holder and said support means, and means for moving both slides in their respective ways to displace the holder toward and laterally of the said support means to produce adjacent alternate bends in the plastic portion of the vitreous tube.

4. Apparatus for bending a vertically disposed vitreous tube comprising means for heating an intermediate portion of the tube to a plastic condition, support means adjacent the heating means for retaining the lower end of the vertically disposed tube at a fixed position, a holder similarly located adjacent the heating means engaging the upper end of the tube for retaining and holding said end in a given relation to the said support means, a vertically disposed slide for supporting the holder, ways defining a vertical path of movement for the slide, means for supporting the slide at one position in the ways during the heating of the tube and thereafter withdrawing said support to allow the force of gravity to displace the slide downward and displace the holder horizontally to produce adjacent alternate bends in the plastic portion of the vitreous tube.

5. Apparatus for bending a vitreous tube comprising means for heating an intermediate portion of the tube to a plastic condition, support

means adjacent the heating means for causing one end of the tube to be retained at a fixed position, a holder similarly located adjacent the heating means engaging the opposite end of the tube for retaining and holding said end of the tube in a given relation to the said support means, a slide for supporting the holder, ways defining a path of movement of the slide in a plane through the holder and the said support means, and means engaging the slide for displacing said slide in the ways both toward and laterally of the said support means to produce adjacent alternate bends in the plastic portion of the vitreous tube.

6. Apparatus for bending a vitreous tube comprising means for heating an intermediate portion of the tube to a plastic condition, support means adjacent the heating means for causing one end of the tube to be retained at a fixed position, a holder similarly located adjacent the heating means engaging the opposite end of the tube for retaining and holding said end of the tube in a given relation to the said support means, a slide for supporting the holder, ways defining a path of movement of the slide in a single plane through the holder and the said support means, means engaging the slide for further defining the path of movement of said slide in said plane in a direction displacing the holder both laterally and toward the said support means, and means for moving the slide in the defined direction in the ways to produce adjacent alternate bends in the plastic portion of the vitreous tube.

7. Apparatus for bending a vitreous tube extending from an end of the envelope of a lamp comprising a movable holder engaging the envelope of the lamp, a second movable holder spaced from the first-mentioned holder and normally disposed in axial alignment therewith and adapted to retain and hold an end portion of the vitreous tube, means for moving the first-mentioned holder axially toward the said second holder to reposition the lamp and direct the end portion of the vitreous tube into proper engagement therewith, burners adjacent the holders for heating an intermediate portion of the tube to a plastic condition, slide means for supporting the said second holder, ways defining a path of movement of the slide means in a direction making an acute angle with the normal line of alignment between said holders, and means engaging the slide means for displacing said slide means in the ways to produce adjacent alternate bends in the plastic portion of the vitreous tube.
